FIG. 4

INVENTOR.
David S. Green:
BY *Emil Staree*
ATTORNEY.

UNITED STATES PATENT OFFICE.

DAVID S. GREEN, OF ST. LOUIS, MISSOURI.

CUSPIDOR.

No. 845,944.

Specification of Letters Patent.

Patented March 5, 1907.

Application filed December 15, 1906. Serial No. 348,022.

To all whom it may concern:

Be it known that I, DAVID S. GREEN, a citizen of the United States, residing at St. Louis, State of Missouri, have invented certain new and useful Improvements in Cuspidors, of which the following is a full, clear, and exact description, reference being had to the accompanying drawings, forming a part hereof.

10 My invention has relation to improvements in cuspidors, (specially adapted for use in railway-cars;) and it consists in the novel construction and arrangement of parts, more fully set forth in the specification and 15 pointed out in the claims.

In the drawings, Figure 1 represents a section of a car-floor, showing my invention applied thereto and showing a chair behind the 20 cuspidor, the latter being depressed below the car-floor and out of commission. Fig. 2 is a similar view showing the cuspidor in operative position. Fig. 3 is a horizontal section on line 3 3 of Fig. 1, the floor being removed and parts being broken away. Fig. 4 25 is a vertical section on line 4 4 of Fig. 3. Fig. 5 is a sectional detail of the cuspidor, showing the discharge-plug therefor in open position; and Fig. 6 is a sectional detail on line 6 6 of Fig. 2.

30 The object of my invention is to provide railway-cars with a cuspidor which may be depressed below the car-floor when not in use, one whose contents can be readily discharged, one easily manipulated, and one possessing 35 further and other advantages better apparent from a detailed description of the invention, which is as follows:

Referring to the drawings, C represents a 40 section of a car, S a chair or seat, and F the car-floor. Located at and secured to the side of the car is a casing 1, terminating in an upper enlarged chamber 1', within which is mounted a lever 2, the shank of whose terminal knob 3 operates in a curved slot 4 in the 45 casing-wall, the lever having pivotally coupled thereto the upper end of a link 5, confined in the casing 1, the lower end of the link projecting through the car-floor and being pivotally secured to the adjacent end of an arm 50 6. The arm 6 has its opposite end rigidly secured to a bar 7, which is secured against rotation (about its own axis) to a lug 8, depending from the end of the short arm of a vertically-oscillating bent lever 9, pivotally 55 suspended by studs or trunnions 10, mounted in the angle-brackets 11, secured beneath the

car-floor. The upper end of the short arm of the lever 9 carries a buffer 12, of rubber or equivalent composition. Secured to the long arm of the lever 9 is one end of a spring arm 60 or plate 13, whose free end bears yieldingly against the car-floor, the purpose of which will presently appear. To the long arm of the lever 9 is secured the spittoon or cuspidor 14, the bottom of whose side wall is provided 65 with a discharge-opening 15, adapted to be closed by a conical plug 16, Fig. 4, the plug having a looped stem 17 projecting through the opening 15, by which the plug can be manipulated or forced inwardly, Fig. 5, to 70 allow for the discharge of the spittoon contents. The spittoon occupies a position immediately below an opening 18, cut in the floor, the said opening being normally closed by a lid 19, hinged to the car-floor, the lid being drawn to its closed position upon a depression of the spittoon through the spring connection 20, the ends of the spring being connected to the lid 19 and to the lever 9, respectively, as shown. To the outer wall of 80 the chamber 1' is hinged a hook or latch 21, which is adapted to engage the shank of the knob 3, Fig. 2, and thus hold the lever 2 and the parts suspended therefrom in a raised 85 position.

When the spittoon is not in use, the parts are released from the latch, Figs. 1, 4, the weight of the spittoon depressing the long arm of the lever 9, which in turn draws the lid 19 after it, closing the opening 18 in the 90 floor. In the drop of the parts to such inoperative position any sudden impact is arrested by the buffer 12, which thus strikes the floor of the car. To prevent undue jars and vibrations of the spittoon incidental to 95 the travel of the car, the spring 13 comes into play, as its resiliency will tend to hug the car-floor, and thus afford a permanent yielding and elastic support to the depressed spittoon while the car is in motion. So, too, whatever may be the extent of the oscillations or vibrations to which the spittoon may be subjected the contractile nature of the spring 20 will always keep the lid 19 closed. To use 100 the spittoon, the traveler raises the lever 2 by 105 seizing the knob or handle 3, then passes the hooked end of the latch 21 under the shank of the knob, thereby retaining the parts in their raised position, Fig. 2. In its upward 110 oscillation the spittoon causes the lug or ear 22 to engage the lid 19 near the hinge-axis of the latter, thereby forcing the lid to an open

position, when the cuspidor can be used for its legitimate purpose.

When depressed below the car-floor, Fig. 4, the cuspidor is readily accessible to the 5 train hands, where it may be flushed with a hose and its contents allowed to discharge by forcing inwardly the plug 16, Fig. 5.

It is of course obvious from the connections described that the lever 9 is free to oscillate about the axis of its trunnions 10 for a 10 movement of the link 5 in either direction.

Having described my invention, what I claim is—

1. In combination with a floor provided 15 with an opening, a lid hinged thereto above the opening, a bent lever pivoted on supports beneath the floor at a point intermediate its length and carrying a cuspidor on one arm thereof, a connection between the lid and lever, a lug depending from the opposite arm of the lever, a bar projecting from said lug, an 20 arm secured to the bar, a link passing upward through the floor and pivotally coupled to the arm, and means for controlling the 25 link from a point above the floor, the parts operating substantially as set forth.

2. In combination with a car-floor provided with an opening, a lid hinged thereto

above the opening, a bent lever pivoted on supports beneath the floor to move about an 30 intermediate axis; a cuspidor on one arm of the lever positioned beneath the opening to move upward through the same, a spring connecting said arm to the lid, a lug depending from the end of the opposite arm of the 35 lever, a rigid horizontal bar secured to the lug, an arm rigidly extending from the bar, a link extending through the car-floor and pivotally connected at its lower end to the adjacent end of the arm, a spring-arm secured 40 to the arm of the lever carrying the cuspidor and having a free end yieldingly bearing against the car-floor, a buffer at the end of the opposite arm of the lever, a lever pivoted above the car-floor and coupled to the upper 45 end of the link, and a latch for securing the link in an elevated position, the parts operating substantially as, and for the purpose set forth.

In testimony whereof I affix my signature 50 in presence of two witnesses.

DAVID S. GREEN.
